CLAIM

An ornamental design for a foldable/portable resting pad for a semi-truck, as shown and described.

DESCRIPTION

FIG. 1 is a schematic perspective from a top front view showing the new design for a foldable/portable resting pad for a semi-truck in its extended position.

FIG. 2 is a schematic perspective from a bottom rear view illustrating an example of the foldable/portable resting pad for a semi-truck in its extended position.

FIG. 3 is a schematic perspective from a top plan view illustrating an example of the foldable/portable resting pad for a semi-truck in its extended position.

FIG. 4 is a schematic perspective from a bottom plan view illustrating an example of the foldable/portable resting pad for a semi-truck in its extended position.

FIG. 5 is a schematic perspective from a left view illustrating an example of the foldable/portable resting pad for a semi-truck in its extended position.

FIG. 6 is a schematic perspective from a right view illustrating an example of the foldable/portable resting pad for a semi-truck in its extended position.

FIG. 7 is a schematic perspective from a front elevation view illustrating an example of the foldable/portable resting pad for a semi-truck in its extended position.

FIG. 8 is a schematic perspective from a rear elevation view illustrating an example of the foldable/portable resting pad for a semi-truck in its extended position.

FIG. 9 is a schematic perspective from a top view illustrating an example of the foldable/portable resting pad for a semi-truck in its closed position.

FIG. 10 is a schematic perspective from a bottom view illustrating an example of the foldable/portable resting pad for a semi-truck in its closed position.

FIG. 11 is a schematic perspective from a top plan view illustrating an example of the foldable/portable resting pad for a semi-truck in its closed position.

FIG. 12 is a schematic perspective from a bottom plan view illustrating an example of the foldable/portable resting pad for a semi-truck in its closed position.

(Continued)

FIG. 13 is a schematic perspective from a left view illustrating an example of the foldable/portable resting pad for a semi-truck in its closed position.

FIG. 14 is a schematic perspective from a right view illustrating an example of the foldable/portable resting pad for a semi-truck in its closed position.

FIG. 15 is a schematic perspective from a front elevation view illustrating an example of the foldable/portable resting pad for a semi-truck in its closed position; and,

FIG. 16 is a schematic perspective from a rear elevation view illustrating an example of the foldable/portable resting pad for a semi-truck in its closed position.
